UNITED STATES PATENT OFFICE.

ALVIN J. WINGE, OF BLANCHARDVILLE, WISCONSIN.

ANCHORING SYSTEM.

Application filed February 5, 1923, Serial No. 617,006. Renewed January 22, 1926.

To all whom it may concern:

Be it known that I, ALVIN J. WINGE, a citizen of the United States residing at Blanchardville, in the county of Lafayette and State of Wisconsin, have invented new and useful Improvements in Anchoring Systems, of which the following is a specification.

This invention relates to improvements in silos and the like, the general object of the invention being to provide bracing means for the silo to prevent the same from getting out of plumb and to prevent twisting thereof.

Another object of the invention is to so arrange the parts that the braces can be tightened by a person standing on the ground thus rendering the use of a ladder unnecessary and also to permit tightening of the staves without interfering with the bracing means.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of a silo provided with my invention.

Figure 2 is a similar view showing the arrangement of braces adjacent the door frame.

Figure 3 is an enlarged sectional view.

Figure 4 is a view of one of the anchor strips.

Figure 5 is a section on line 5—5 of Figure 1.

Figure 6 is a section on line 6—6 of Figure 1.

In these views 1 indicates the staves of the silo and 2 the concrete foundation thereof.

In carrying out my invention I place anchor strips 3 in the foundation with their upper ends projecting therefrom, said ends being spaced from the staves but connected therewith by the bolts 4. The lower ends of the strips are rolled to provide eyes 5 and eyes 6 are formed on the upper ends. A rod 7 is threaded through the eyes 5, said

rod being embedded in the concrete foundation. Plates 8 are bolted to the staves by bolts 9 which also engage bent up extensions of the plates which form hooks 10. A pair of converging brace rods 11, having eyes at the upper ends, engage each of the hooks 10 and the lower ends of these rods 11 are threaded to receive turn buckles 12, each turn buckle having its lower end engaged by a left hand threaded rod 13 which is provided with a hook 14 for engaging the eye 6 of a strip 3. This turn buckle arrangement permits the braces to be adjusted and as they are located close to the foundation they can be turned by a person standing on the ground so that a ladder is not necessary. A pair of plates substantially similar to the plates 8 are bolted to the door frame, as shown at 8', and each of these plates 8' receives a single brace rod instead of two brace rods, as the other plates. I prefer to use eight brace rods arranged in four pairs, as shown in Figures 1 and 2, so that the braces prevent the silo from twisting and also from getting out of plumb. There is a direct pull on the foundation anchors which prevents any upward movement of the parts of the silo. As each of the plates 8 is fastened to a single stave the braces will not interfere with the tightening of the staves.

Hooks 15 are bolted to the top portion of the sides of the silo and overlie the top as shown. These hooks are connected with the plates 8 and 8' by the rods 16 which have screw threaded ends passing through holes in ears 8^x formed on the plates 8 and 8' and through holes in the ears 16^x on the hooks 15. Nuts 17 engage the screw threaded ends of the rods for adjusting the parts so that the plates will be braced from the top of the silo.

By arranging the parts in the manner heretofore described and as shown in the drawing substantially six of the rods will, at all times, be receiving the strain from the silo, which will be caused by a heavy wind, thereby distributing the wind strain and thereby rendering a more secure and durable anchoring structure for preventing the blowing over, twisting or warping of the silo.

It is thought from the foregoing description that the advantages and novel features of my invention will be readily apparent.

I desire it to be understood that I may make changes in the construction and in the

combination and arrangement of the several parts, provided that such changes fall within the scope of the appended claims.

What I claim is:—

- 5 1. In a silo, anchor strips embedded in the foundation thereof, means for bolting each strip to a stave of the silo, hooked plates bolted to other staves thereof, each plate being connected with a single stave, 10 brace rods having their upper ends engaging the hooks of the plates and their lower ends the anchor strips, turn buckles forming portions of the rods and adjustable means for connecting the plates with the top of 15 the silo.

2. A silo anchor of the character described comprising strips adapted to be embedded a

portion of their length in a concrete foundation for the silo, and having their ends provided with eyes, an annular rod threaded 20 through the eye in the lower ends for associating the strip as a unit, bolts having one end secured to the strips and their opposite ends secured to the silo for spacing said strips therefrom, hook bearing plates secured to the silo at spaced intervals, a plurality of rods arranged in converging pairs having their ends secured to the strips and plates respectively, hooks having portions 25 overlying the top edges of the silo and means 30 of connection between the hooks and plates as and for the purpose specified.

In testimony whereof I affix my signature.

ALVIN J. WINGE.
